United States Patent [19]**Noodeljik****Patent Number: Plant 11,644****Date of Patent: Nov. 21, 2000**[54] **CHRYSANTHEMUM NAMED 'REMCO YELLOW'**[75] Inventor: **Robert Noodeljik**, Woubrugge, Netherlands[73] Assignee: **Chrysanthemum Breeders Association N.V.**, Netherlands[21] Appl. No.: **09/149,461**[22] Filed: **Sep. 9, 1998**[51] Int. Cl.⁷ ..... **A01H 5/00**[52] U.S. Cl. .... **Plt./295**[58] Field of Search ..... **Plt./286, 295, 296***Primary Examiner*—Howard J. Locker**ABSTRACT**

A new and distinct cultivar of chrysanthemum plant named Remco Yellow, bearing medium sized blooms with yellow ray florets and a greyed-orange center and performance of 21 days.

2 Drawing Sheets**1**

The present plant is related to the plant in the following co-pending application:

application Ser. No.	Filing Date	Title
09/149,459	9/9/98	Remco

BACKGROUND OF THE INVENTION

The present invention comprises a new and distinct cultivar of chrysanthemum plant which is a natural occurring sport of a parent chrysanthemum named Remco. Patent chrysanthemum Remco is also described in this application. The new cultivar was discovered as a whole plant mutation in 1993 by R. Noodeljik in a controlled environment (greenhouse) in Ter Aar, Holland. The first act of asexual reproduction of Remco Yellow was accomplished when vegetative cuttings were taken from the initial selection in Aug. 1993 in Ter Aar, Holland.

SUMMARY OF THE INVENTION

The present invention is a new and distinct variety of chrysanthemum bearing medium sized blooms with yellow ray florets and a greyed-red center.

BRIEF DESCRIPTION OF THE DRAWINGS

The present invention of a new and distinct variety of chrysanthemum is shown in the accompanying drawings, the color being as nearly true as possible with color photographs of this type.

FIG. 1 shows the stem of the cultivar in full bloom.

FIG. 2 shows the various stages of bloom of the new cultivar.

FIG. 3 shows the foliage and petiole of the new cultivar.

DESCRIPTION OF THE INVENTION

This new variety of chrysanthemum is of the botanical classification *Dendranthema grandiflora*. When grown in the vicinity of Ter Aar, Holland, it has a response time of approximately 8 weeks. This new variety produces medium sized blooms with yellow ray florets and a greyed-red center having a 3 week performance (i.e., vase life of 21 days). This new variety of chrysanthemum has been found to retain its distinctive characteristics throughout successive propagations. However, the phenotype may vary significantly with

variations in environment such as light intensity and temperature. To show the phenotype as described Remco Yellow may be planted under greenhouse conditions in Holland without assimilation lightning between week 2 and 40. With assimilation lightning (minimum level 2500 lux) Remco Yellow may be planted year round under greenhouse conditions in Holland.

The following is a description of the plant and characteristics (color designations are from the R.H.S. Colour Chart) that distinguish it from related known varieties and its antecedents:

The color designations are taken from the plant itself. Accordingly, any discrepancies between the color designations and the colors depicted in the photographs are due to photographic tolerances.

Botanical Description of Remco Yellow and Remco

CULTIVAR	REMCO YELLOW	Parent Cultivar REMCO
<u>Bud</u>		
Size	Large cross section ± 1.5 cm height ± 1.2 cm	large cross section ± 1.5 cm height ± 1.2 cm
Outside Color	yellow-orange 21A to red 46A at the tip	mainly red 49 D, red-purple 64 D at the tip
<u>Bloom</u>		
Size	medium	medium
Fully Expanded	6-6½ cm	6-6½ cm
Borne	upper portion single flower per peduncle, lower portion plural flower per peduncle	upper portion single flower per peduncle, lower portion plural flower per peduncle
Number of Blooms per single stem	average of 11	average of 11
Peduncle Lengths	Near the top ± 12 cm, near the middle ± 26 cm, near the bottom ± 28 cm.	Near the top ± 12 cm, near the middle ± 26 cm, near the bottom ± 28 cm.
Peduncle Lateral Shoot, Attachment	weak to medium	medium
Peduncle Lateral Shoot, Angle	35°-30°	40°
Form	semi-double (anemone)	semi-double (anemone)
Performance (lastingness of the total inflorescence)	good 21 days (18°-20° C.)	good 21 days (18°-20° C.)
Color		
Center of Flower/ Disc floret	Greyed-orange 170 A with a dot in the very center of greyed-red 178 C	Between orange-red 33 B and 34 A with a dot in the very center of red 53 B

Botanical Description of Remco Yellow and Remco		
CULTIVAR	REMCO YELLOW	Parent Cultivar REMCO
Color of the upper surface of the majority of the ray-florets	Yellow-orange 16 A	red-purple 69C but slightly more white
Color of the lower surface of the majority of the ray-florets.	yellow 10C with greyed-red 182D between the ribs	red-purple 69B but slightly paler
Tonality from Distance	a yellow anemone type flower with a red tint and a greyed-orange cushion	a pinkish white anemone type flower with an orange-red cushion
Discoloration	ray-florets to yellow-orange 16 C, cushion to yellow 13A with greyed-red 178A at the tips	ray-florets to almost white, center (cushion) to orange-red 34 C
Pollen Ray florets	(not present)	(not present)
Texture	upper side smooth, underside smooth	upperside smooth, underside smooth
Number	25–30 (two rows)	25–30 (two rows)
Cross-section	convex, two keels	convex, no keels
Longitudinal axis of majority	straight	reflexing
Shape of tip	rounded	dentate
Fragrance	typical chrysanthemum	typical chrysanthemum
Disc Diameter	large to very large (2.5–3.0 cm)	large to very large (2.5–3.0 cm)
Reproductive Organs		
Stamen (present in disc florets only)	yellow-green, thick ± 5 mm in length	yellow-green, thick ± 5 mm in length
Pollen	(not present)	(not present)
Styles (present in disc and ray florets)	green, thick	green, thick
Style Length	± 7 mm	± 7 mm
Stigmas	yellow-green	yellow-green
Stigma Width	± 3 mm	± 3 mm
Ovaries	enclosed in calyx	enclosed in calyx
Plant		
Form	spray mum meant for erect culture Herbaceous	spray mum meant for erect culture Herbaceous

Botanical Description of Remco Yellow and Remco		
CULTIVAR	REMCO YELLOW	Parent Cultivar REMCO
Growth	medium	medium
Height	± 110 –120 cm	± 110 –120 cm
Stem Color	green 146A	green 139A
Stem Strength	medium to strong	medium to strong
Stem Brittleness	present	absent
Stem Anthocyanin	present (mainly at the base)	present (mainly at the base)
Internodes	medium (2.5–3.0 cm)	medium (2.5–3.0 cm)
Flowering Response (photoperiodic controlled crop, no natural growing)	8 weeks	8 weeks
Foliage		
Color	upper side between 137A and yellow-green 147A, underside near green 137B	upper side between 137A and yellow-green 147A, underside near green 137B
Size	length ± 12 cm, width ± 6 cm	length ± 12 cm, width ± 6 cm
Quantity (per single stem)	22–26	22–26
Shape	lobed	lobed
Texture	fleshy	fleshy
Ribs and Veins	ribs well developed, veins not so developed	ribs well developed, veins not so developed
Edge	crenated	crenated
Shape of Base of Sinus Between Lateral Lobes	round	round
Margin of Sinus Between Lateral Lobes	converging	converging
Shape of Base	uneven	uneven
Apex	cuspidate	cuspidate
Year of Discovery	1993	1992

I claim:

1. A new and distinct variety of chrysanthemum plant as described and illustrated.
